UNITED STATES PATENT OFFICE.

STUART BERTRAM BOOTY, OF EAST PERTH, WESTERN AUSTRALIA, AUSTRALIA, AS
SIGNOR OF ONE-HALF TO JAMES ABSALOM TURNER, OF PERTH, WESTERN AUSTRALIA, AUSTRALIA.

MAGNETO ACCELERATOR.

Application filed February 24, 1921. Serial No. 447,605.

To all whom it may concern:

Be it known that I, STUART BERTRAM BOOTY, a subject of the King of Great Britain and Ireland, residing at 69 Moore Street, East Perth, Western Australia, in the Commonwealth of Australia, have invented new and useful Improvements in Magneto Accelerators, of which the following is a specification.

- 10 This invention relates to an improved magneto accelerator, that is to say, it relates to an apparatus for giving a rapid rotary impulse to the magneto spindle, thereby producing an intensely hot spark.
- 15 It is well known that the cranking up to start internal combustion engines is frequently a difficult operation often requiring several attempts before the engine fires. This difficulty is caused through the spark produced by the magneto not being hot enough to ignite the mixture. Even when a self starter is used the starting motor must usually rotate some little time before it acquires a speed sufficient to cause the magneto to give a spark of the required temperature and this means that the life of the batteries supplying current to the motor is much shorter than if the engine started almost at once.
- 20 Means have previously been devised having for their object to give the magneto spindle a very rapid acceleration almost immediately after commencing to turn the crank or in the case of a self starter after the motor commenced to drive and consequent upon such rapid acceleration immediately producing a very hot spark which ignited the mixture and so started the engine.
- 25 In practical operation, however, the aforesaid means have either not given the desired accelerating impulse to the magneto spindle or else have been defective in that the accelerating means have from time to time accidentally fallen into gear when the magneto is revolving at a high rate of speed, with of course, disastrous results to the apparatus.

Now the primary object of the present invention is to provide means whereby the accelerating device is readily thrown into action when it is desired to start the motor and is thrown and positively kept out of action when the accelerating impulse has

10 The invention consists, broadly, in holding the magneto spindle against rotation by a pawl which forms one end of a pivoted member, the other end of which is formed as a cam. When the pawl is thrown out of engagement with the magneto spindle it is held out of engagement through the medium of the cam end of the said member.

To enable the invention to be more readily understood I will now refer to the accompanying sheet of explanatory drawings wherein—

Fig. 1 shows an elevation of the apparatus partly in section and in the position it occupies before attempting to start the engine.

Fig. 2 also shows an elevation partly in section but having the parts in the relative position they will occupy just before the accelerating impulse is given, and

Fig. 3 is a plan of the pawl and cam member.

In the drawings, the magneto spindle 10 has keyed thereto a sleeve 11 formed integral with which is a disc 12 formed with an upright stop 14 and also having two notches 13 cut therein. Turning loosely on the collar 11 is a driving member in the form of a spring barrel 15 the channel 16 of which at one part is formed with a stop 17. The barrel 15 also has two lugs or cams 18 oppositely disposed on the outside thereof and also screw holes 19 for attaching to a flange or the like on to the magneto drive shaft. A metal plate 20 is attached to the magneto body and this plate has attached a pivot 21 on which turns a member one end 22 of which acts as a pawl whilst the other end acts as a cam. The working face of the said pawl is cut away slightly at 23 so as to give an overhanging portion 24 of the pawl which is the portion actually struck by the lugs or cams 18. The cam end of the member is cut away to afford clearance for the lower end of a control lever 25 and it is formed with two faces 26 and 27 and of these faces the face 27 is further from the pivot 21 on which the member turns. The control lever 25 is pivoted at 28 and to it is attached a pin 29 connected to which is one end of a tensional spring the other end of which is attached to a similar pin 30 on the pawl and cam member a little above the pivot 21. A stop 31 is attached to the plate 20 so as to limit

100 110
105 115
110

the anti-clockwise movement of the control lever 25.

The operation of the apparatus is as follows:—When it is desired to start the engine 5 the control lever 25 is turned in a clockwise direction and held preferably by a cord, thereby throwing the pawl 22 into the path of the notches 13 one of which it will subsequently engage. The crank is then turned 10 whereby a torque is applied to the spring barrel 15 (through the screw holes 19) with the result that the stop 17 compresses one end of the spring the other end of which presses against the stop 14 of the disc and 15 so tries to turn the magneto spindle being prevented however by the pawl 22 holding a notch 13. The result is that the barrel 15 commences to turn against the compression of the spring until a lug or cam 18 reaches 20 the pawl and acting on the face 24 thereof throws it out of engagement with the notch 13. The disc 12 is thereby released and the kinetic energy stored in the compressed spring gives a very strong accelerating 25 pulse thereto (and consequently to the attached magnet spindle) turns the magneto armature rapidly over the ignition point and so causes explosion of the mixture. When the disc 12 has been turned by the spring 30 around to its normal position relatively to the spring barrel it continues to be driven by its stop 14 being continuously pressed by the spring.

When the pawl is thrown out of engagement with a notch by one of the lugs 18 the cam face 26 is pulled by a spring against the pin 29, and as the cam face 27 is further from the pivot 21 than the face 26 it will be necessary to stretch the spring if the member is to turn back so as to again throw the pawl into the path of the notch. The result of this construction is that the pawl is precluded from accidentally moving into engagement with a notch although it readily 45 turns in when the control lever is turned and moves the pin 29 away from the cam face 26 and simultaneously pulls the spring.

I claim:—

1. In a device of the character described, 50 the combination with a notched member adapted to be attached to a magneto spindle, of a pawl member pivoted intermediate of its ends and having at one end a pawl adapted to be moved into engagement with 55 the notched member thereby to prevent it from turning, the opposite end of said pawl member having a cam face, a driving member adapted to be connected to the magneto shaft, a spring connection between said driving member and notched member, a spring connected to the pawl member and co-operating with the cam face to hold the pawl normally out of engagement with the notched member, means co-operating with 60 said spring by which the pawl member is

thrown into operative position, and means to disengage the pawl from the notched member.

2. In a device of the character described, the combination with a notched member 70 adapted to be attached to a magneto spindle, of a pawl member pivoted intermediate of its ends and having at one end a pawl adapted to engage said notched member thereby to prevent it from turning, the opposite end of said pawl member having a cam face, a driving member adapted to be connected to the magneto shaft, a spring connection between said driving member and notched member, a spring connected to the 80 pawl member, movable means co-operating with said spring and cam face for holding the pawl normally in inoperative position out of engagement with the notched member, movement of said means operating through the spring to move the pawl into operative position in engagement with the notched member, means co-operating with the cam face on the pawl member to hold the pawl in such operative position, and means to disengage the pawl from the notched member by movement of the driving member. 90

3. In a device of the character described, the combination with a notched member adapted to be attached to a magneto spindle, of a pawl member pivoted intermediate of its ends and having at one end a pawl normally out of engagement with the notched member but adapted to be moved into engagement therewith thereby to prevent it from turning, the opposite end of said pawl member having a cam face, a driving member adapted to be connected to the magneto shaft, a spring connection between said driving member and notched member, a spring connected to the pawl member, means co-operating with said spring by which the pawl member is thrown into operative position, said means adapted to hold the pawl either in operative 100 or inoperative position, and means to disengage the pawl from the notched member by movement of the driving member. 105

4. In a device of the class described, the combination with a notched member 115 adapted to be attached to a magneto spindle, of a pawl member pivoted intermediate of its ends and having at one end a pawl adapted to engage the notched member and prevent it from turning, the opposite end of said pawl member having two cam faces, a rotary driving member having a cam, a spring forming a driving connection between the driving member and the notched member, a pivoted controlling lever having a portion to engage the cam faces of the pawl member, and a spring connecting the pawl member to the controlling lever, whereby in one position of the lever 120 the spring connected to the pawl member co- 125

- operates with the controlling lever and one cam face to hold the pawl member in inoperative position, and another position of the controlling lever said spring co-operates 5 with the pawl member and the other cam face to hold the pawl member in operative position.
5. In a device of the class described, the combination with a notched disc adapted 10 to be keyed to a magneto spindle, of a spring barrel loosely surrounding said spindle and adapted to be connected to a magneto driving shaft, a spring forming a driving connection between the spring barrel 15 and the notched disc, a pawl member pivoted intermediate of its two ends and having one end formed as a pawl to engage said notched disc and having the other end formed with a cam face, a movable pin operating against said cam face, a spring connecting said pin with the pawl member and 20 means to disengage the pawl from the notched disc by the rotation of the spring barrel.
6. In a device of the class described, the combination with a notched disc connected 25 to a magneto spindle, of a spring barrel loosely surrounding said spindle and adapted to be connected to the magneto driving shaft, a cam on the spring barrel, 30 a spring forming a driving connection between said spring barrel and notched disc, a pawl member pivoted intermediate of its two ends and having one end formed as a pawl to engage said notched disc and the 35 other end provided with a cam face, a pivoted control lever, a pin connected to the said control lever and working against said cam face, a spring connecting the aforesaid pin with the cam member, and means to disengage the pawl from the notched disc by 40 the rotation of the spring barrel.

Dated this fifteenth day of January, 1921.
STUART BERTRAM BOOTY.
